UNITED STATES PATENT OFFICE.

ROBERT GOULD JENNINGS, OF ELMIRA, NEW YORK.

YARN CLEANER.

Application filed March 15, 1920. Serial No. 385,788.

To all whom it may concern:

Be it known that I, ROBERT G. JENNINGS, a citizen of the United States, residing at Elmira, in the county of Chemung and 5 State of New York, have invented certain new and useful Improvements in Yarn Cleaners, of which the following is a full, clear, and exact description, such as will enable others skilled in the art to which it 10 appertains to make and use the same.

This invention relates to yarn cleaners, and with respect to some of its more specific details, to yarn cleaners of the character disclosed in prior Patent No. 1,301,133 15 granted April 22, 1919, reissued March 16, 1920, No. 14,818.

It is an object of this invention to provide an improved means for separating impurities from yarn so as to produce a clean and 20 finished product.

It is a further object to provide an improved releasing means for a yarn cleaning unit of the type disclosed in said prior patent.

25 It is a further object to provide an improved means to release the impurities collected by yarn cleaning mechanism, while at the same time maintaining uniform tension on the yarn.

30 It is a further object to provide improved means for mounting the moving parts of a yarn cleaning unit on its supporting bar.

Other objects will be in part obvious and 35 in part pointed out in connection with the following detailed description of the invention.

The invention accordingly consists in the 40 features of construction, combinations of elements and arrangement of parts which will be exemplified in the construction herein-after set forth, and the scope of the application of which will be indicated in the following claims.

In the accompanying drawings wherein an 45 illustrative but preferred embodiment is shown,

Figure 1 is a plan view of a yarn-cleaning apparatus embodying the invention;

Fig. 2 is a side elevation thereof;

50 Fig. 3 is an enlarged sectional view taken on the line 3-3 of Fig. 1;

Fig. 4 is a fragmentary sectional elevation taken approximately on the line 4-4 of Fig. 1;

55 Fig. 5 is a fragmentary sectional elevation on the line 5-5 of Fig. 1;

Fig. 6 is a detailed fragmentary sectional elevation taken approximately on the line 6-6 of Fig. 2 looking in the direction indicated by the arrow;

60

Fig. 7 is a fragmentary enlarged plan view of one of the yarn cleaning units;

Fig. 8 is a side elevation thereof;

Fig. 9 is an enlarged sectional elevation on the line 9-9 of Fig. 2; and

65

Fig. 10 is an enlarged fragmentary side elevation of the operating mechanism for one of the cleaning units, parts being broken away and parts shown in section on a plane between the blades of the cleaning unit to 70 disclose structural details more clearly.

As shown in the illustrative embodiment, a rectangular supporting bar 1 carries six cleaning units, 2, 3, 4, 5, 6, and 7, spaced along its length, and is provided at its forward end with a tension device 8. Mounted adjacent the tension device on the supporting bar 1 is a guiding loop 9 through which the yarn is adapted to pass.

75

Each cleaning unit is provided with a bed 80 10 fixed to the bar 1 and having an upper surface comprising a generally flat portion merging into a downwardly curved portion. The gripping device 11 for gripping and holding the impurities collected from the 85 yarn includes blades 11^a and 11^b which are pivotally mounted side by side on bar 1 by means of a pin 12. Each blade has an extended portion curved on its lower surface, the radius of curvature differing from that of the upper curved surface of the base 10, thus providing a wedge shaped opening 10^a, when the blade is in contact with the bed, 90 which receives and holds the impurities as they are removed from the yarn. This construction is similar to that disclosed in said prior Reissue Patent No. 14,818 above referred to.

95

The pin 12 extends through a squared aperture in a laterally disposed projection 13 on each of the blades, and to prevent the blades from angular movement with respect to said pin the latter is squared for a short distance adjacent the blades as shown in Fig. 10. A washer 14^a having a squared aperture 100

therein is provided on the squared portion of the pin 12 just outside the projection 13 of the blade 11^a adjacent the place on the pin 12 where the square and circular sections thereof merge. Thus it will be seen that the washer 14^a abuts against the shoulders formed by these merging sections to hold the 105 110

blades on the pin when the latter is removed from the supporting bar 1, the nut 12^a being employed for this purpose to engage the outer blade 11^b. At a reduced portion 12' at one end of the pin 12 a thread is provided to receive the nut 12^a which adjustably holds the blades in position on the squared portion of the pin. Two spaced sleeves or thimbles 14 and 15 are disposed 10 on opposite sides of the bar 1 and have reduced portions 14' and 15' respectively which extend into apertures in the bar 1 approximately half way through the latter from each side leaving a small slot 16 between the ends thereof for receiving lubricating oil. These sleeves are provided with circular apertures for receiving and acting as bearings for the pin 12 which projects beyond the sleeve 15 to receive a block 17 which has 15 an aperture for this purpose. The block 17 is provided with a set-screw 17' for securing it in position on the pin, and is further provided with a slot or seat 18 to receive the end of a spring arm 19. This spring arm extends 20 downwardly from the block 17, as shown in Figs. 9 and 10, and at its upper end is looped upon itself as at 20 having a reversely extending portion 21 lying in said seat 18. This provides for the operating 25 spring arm 19, a terminal connecting portion having spaced sections resiliently connected by the bent part 20, and lying in a plane disposed substantially at right angles to the axis of pin 12. Extending through 30 the upper terminal portion of the spring arm adjacent the looped portion thereof into the block 17 is an adjusting and securing screw 22 by which the lower portion of said arm may be readily adjusted. This adjusting screw is securely held in adjusted position by means of a locking screw 22' which is 35 adapted to be screwed into the block 17 to engage the periphery of the adjusting screw. An oil hole 1^a is disposed in the bar 1 and 40 above slot 16 whereby oil may be inserted to lubricate the rod 12 in its bearings. 45

The gripping blades of each cleaning unit are yieldingly held in gripping relation with the bed 10 by means of a double coiled spring having opposed coils 23 and 24 surrounding the pin 12 between the blades. As shown in Fig. 6 of the drawing, the two coils may be conveniently formed from a single length of spring wire so as to form in effect a 50 single spring having an extension 25 near its center which is looped about an anchor pin 26, the free end of each coil being looped as at 27 to engage the respective blades. The opposed spring coils engage the blades to hold the latter apart in 55 spaced relationship with respect to each other on the pin 12, and the distance between the blades may be adjusted by nut 12^a. It will thus be seen that the spring not only 60 yieldingly holds the blades apart in spaced

relationship but also yieldingly holds them from moving apart due to the fact that the portions of the extension 25 adjacent the periphery of the nut 12^a and washer 14^a act as fulcrums when either blade moves away from the other, causing the adjacent portions of the extensions to compress the spring. By this construction the space between the blades is automatically adjusted to different diameters of yarn or to irregularities in the same yarn so that the blades are always held lightly in yielding engagement therewith. 75

As shown in Fig. 7, an integral lug 29 extends from the looped portion 21 of the arm 19 adjacent the block 17 in position to engage the rear end to the bed 10 to limit the upward or releasing movement of the blades. 80

As shown in Figs. 1 and 3 an additional guiding loop 30 for the yarn is secured in position near the rear end of supporting bar 1, and mounted adjacent this loop on said bar is a guide plate 31 having a slot 32 through which the yarn passes. 85

As in Reissue Patent No. 14,818, above referred to, releasing means are provided for moving the blades of each cleaning unit at intervals to release the impurities which have been collected from the yarn and gripped or wedged into the slot 10'. According to this 90 invention improved means are provided for this purpose, operating the blades alternately in groups so as to preserve as nearly as possible a uniform resistance to the passage of the yarn through the units and to 95 maintain an approximately constant tension at all times. This function is accomplished by the construction which is shown particularly in Figs. 1 and 2 of the drawing. As shown in Figs. 1 and 2 a metallic arm 40 100 is suitably supported on the hub 41 on a supporting rod 42 mounted in brackets 43, and this arm extends parallel to the bar 1 having near the outer end thereof a laterally projecting lug 44, having a pair of spaced apertures 105 therein. The bar 1 is also carried on a projection 41' of the hub 41. Extending through and supported in the apertures in said lug are longitudinally reciprocating rods 45 and 46, the rear ends of which diverge at 47 and 48 110 and are connected to opposite ends of a rocker arm 49 mounted upon and extending on opposite sides of a rock shaft 50, said arm being held in position on said shaft by means of a set-screw 51 and being formed with a suitable aperture 52 for receiving said shaft. 115

Suitably secured in spaced position on the reciprocating rods 45 and 46 as by set-screws are contact lugs 53 having projection 54 lying between the rods and adapted to contact with the arms 19. As shown in Figs. 1 and 10, the contact blocks are spaced on the rod 45 to contact with the arms of alternate 120 cleaning units, and those on rod 46 are 125

spaced to contact with the arms of the remaining cleaning units.

The means for oscillating the shaft 50 to operate the releasing rods 45 and 46 comprises a cam wheel 55 having a groove for a driving belt and a circular cam surface 56 provided with a projection 57 and a depression 58 diametrically disposed with respect to said projection. An arm 59 secured to shaft 50 carries a roller 60 and is urged by the coiled spring 61 to cause the roller to contact the periphery of the cam surface.

A suitable shield 63 may depend from the supporting bar 1 to protect the operating parts, and a guide member 62 may be employed to aid in placing the yarn in operative relationship with respect to the cleaning units.

In operation the yarn to be cleaned is threaded through the tension device 8, between the blades of each cleaning unit, and through the guiding loop 30 and slot 32 at the rear of the supporting bar 1. The thread is then caused to travel at a rapid rate through the cleaning apparatus and the impurities are removed therefrom and jammed into the wedge shaped slots 10 and held by the blades 11^a and 11^b in a manner as is particularly described in said prior Reissue Patent No. 14,818. The thread is lightly pressed between the blades 11^a and 11^b of each unit under the influence of the springs 23 and 24, the pressure exerted upon the blade being readily adjustable by means of the nut 12^a, and by this same means the unit may be adjusted for different sizes of yarn. Irrespective of the size of the yarn, or of irregularities of the same, the blades, by means of spring 23, 24 are held lightly in yielding engagement with the yarn at all times, the movement of the blades due to enlargements on the yarn being yieldingly opposed by the spring by reason of the fact that a portion of the extension 13 of each blade fulcrums at its edge on the adjacent periphery of the washer 14^a in the case of blade 11^a, or of the nut 12^a in the case of 11^b. The tendency therefore is to offer a constant resistance to the passing yarn and to maintain a uniform tension.

As the cam wheel 55 rotates the projection 57 and depression 58 are brought alternately in contact with the roller 59 to operate the mechanism for releasing the impurities lodged in slots 10' of the cleaning units. When the projection 57 engages the roller, the arm 59 and shaft 50 are operated so as to move rod 45 longitudinally toward said shaft while rod 49 moves in the opposite direction. The lugs 53 on the rod 45 will thus be brought into engagement when the adjustable arms 19 of the second, fourth, and sixth cleaning units, counting from the leading end of the supporting bar 1, and the blades of these units will thus be raised to

allow the collected impurities to be swept out of the slot 10' by the rapidly moving yarn. The lugs 43 on the rod 46 will move away from the adjustable arms 19, as shown in Figs. 2 and 8, and the remaining cleaning units will not be released. However, when the depression 58 aligns with the rollers the spring 61 causes the latter to move inwardly moving the rods 45 and 46 in directions reverse to those just described. In this case it will be seen that lugs 53 on rod 46 are brought into contact with the arms 19 of the first, third and fifth cleaning units and the latter are operated to release the impurities, while the remaining units remain stationary. It will thus be seen that the cleaning units are released in alternate groups, with a consequent tendency to maintain a constant tension on the yarn at all times.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described, and all statements of the scope of the invention which, as a matter of language, might be said to fall therebetween.

Having described my invention, what I claim as new and desire to secure by Letters Patent is:

1. In a yarn cleaning apparatus, in combination, means for removing impurities including a support, a pin mounted on said support, a plurality of blades on said pin, and yielding means contacting said pin and anchored to said blades and having an extension anchored in fixed position relatively to said support.

2. In a yarn cleaning apparatus, in combination, a cleaning unit including a support, a pin rotatably mounted on said support, blades on said pin, rotatable therewith, and means disposed between said blades for yieldingly holding the same in gripping position.

3. In a yarn cleaning apparatus, in combination, a pair of blades mounted side by side, means mounted between said blades to yieldingly hold the same in spaced relationship, adjusting means for said blades and means for positively raising said blades to release impurities held thereby.

4. In a yarn cleaning apparatus, in combination, a rotatably mounted pin, a pair of blades mounted on said pin so as to rotate therewith, a supporting bar having an aperture therein, and sleeves disposed on

opposite sides of said bar projecting into said aperture and providing a bearing for said pin.

5. In a yarn cleaning unit, in combination, a pair of blades mounted on a pin so as to rotate therewith, a supporting bar having an aperture therein and sleeves disposed on opposite sides of said bar having reduced portions projecting into said aperture and providing a bearing for said pin.

6. In a yarn cleaning unit, in combination, a rotatably mounted pin, a pair of blades mounted on said pin so as to rotate therewith, a supporting bar having an aperture therein, sleeves disposed on opposite sides of said bar and projecting into said aperture and providing bearings for said pin, and means engaging said blades to yieldingly hold the same in spaced relationship.

7. In a yarn cleaning apparatus, in combination, a cleaning element, a pin carrying said element and rotatable therewith, a block connected to said pin, a looped operating arm, and securing means passing through the looped portion of said arm and into said block.

8. In a yarn cleaning apparatus, in combination, a cleaning element, a pin carrying said element and rotatable therewith, an operating arm for said pin having spaced portions, and means for operatively connecting said arm to said pin including adjustable securing means passing through said spaced portions.

9. In a yarn cleaning apparatus, in combination, a cleaning element, a pin carrying said element and rotatable therewith, an operating arm for said pin having spaced portions resiliently held in spaced relationship, and means operatively connecting said pin and arm.

10. In a yarn cleaning apparatus, in combination, a cleaning unit having a pin, a support for said pin, spaced blades mounted on said pin to rotate therewith, and resilient spacing means mounted between said blades and anchored to said support.

11. In a yarn cleaning unit, in combination, a cleaning unit having a pin, a support for said pin, spaced blades mounted on said pin to rotate therewith, resilient spacing means mounted between said blades and anchored to said support, and means for moving said pin to operate said blades.

12. In a yarn cleaning apparatus, in combination, a cleaning unit having a pin, a support for said pin, spaced blades mounted on said pin to rotate therewith, resilient

spacing means mounted between said blades and anchored to said support, and resiliently adjustable means upon said pin to move the latter.

13. In a yarn cleaning apparatus, in combination, a support, a pin rotatably mounted on said support, a bed, blades mounted on said pin rotating therewith and engaging said bed to limit the movement of said pin in the one direction, means on said pin to operate the same, and a stop carried by said means and adapted to engage said bed to limit the movement of said pin in another direction.

14. In a yarn cleaning apparatus, in combination, a support, a pin rotatably mounted on said support, a bed, blades mounted on said pin rotating therewith and engaging said bed to limit the movement of said pin in one direction, means on said pin to operate the same, a stop carried by said means and adapted to engage said bed to limit the movement of said pin in another direction, and resilient means biased to urge said pin to one of its limiting positions.

15. In a yarn cleaning apparatus, in combination, a cleaning unit, a rotatable operating pin for said unit, an operating arm for said pin having a terminal portion adapted for connection to said operating pin and having resiliently connected sections spaced apart and lying in a plane substantially at right angles to the axis of said pin, and a fastening device co-operating with the sections of said terminal portion for securing said operating arm to said pin and for adjusting said operating arm relatively thereto.

16. In a yarn cleaning apparatus, in combination, a cleaning unit having a rotatable operating pin, an adjustable operating arm connected to said pin, and stop mechanism to limit the movement of rotation of said pin including a stop member on said arm.

17. In a yarn cleaning apparatus, in combination, a cleaning unit, and means for operating said cleaning unit, including an operating arm having spaced terminal sections, resilient means for connecting said sections together, and an adjusting device co-operating with said spaced sections, said adjusting device being normally adjusted to press said sections together against opposition of said resilient connection.

In testimony whereof I affix my signature, in the presence of two witnesses.

ROBERT GOULD JENNINGS.
